UNITED STATES PATENT OFFICE.

HENRY C. EGERTON, OF PASSAIC, NEW JERSEY, ASSIGNOR TO WESTERN ELECTRIC COMPANY, OF NEW YORK, N. Y., A CORPORATION OF ILLINOIS.

TELEPHONE TRANSMISSION-CIRCUITS.

1,089,825.

Specification of Letters Patent. Patented Mar. 10, 1914.

Application filed July 18, 1912. Serial No. 710,108.

To all whom it may concern:

Be it known that I, HENRY C. EGERTON, a citizen of the United States, residing at Passaic, in the county of Passaic and State of New Jersey, have invented a certain new and useful Improvement in Telephone Transmission-Circuits, of which the following is a full, clear, concise, and exact description.

This invention relates to telephone transmission systems for loud speaking apparatus and more particularly to a system in which two independent transmission circuits terminating at a single station each have connected therewith a receiver in interfering proximity with the other.

One of the objects of this invention is to provide means for preventing the interference of one receiver with the other during a period of communication over one of the circuits. This is accomplished in general by providing circuit connections and apparatus so arranged that when the station attendant is connected for communication over one of the circuits, connections will be made which will reduce the volume of sound produced by the other in case conversation is made at the opposite end of the line with which it is connected.

Another object of this invention is to provide a signaling and busy indicating means for use in connection with the circuits. This feature consists in the provision of a signal at each of the stations adapted when operated to put a tone upon the line which will be audible at both ends of the line and the volume of which indicates the condition of the apparatus at the called station.

Other features of this invention will be more particularly described hereinafter and 40 pointed out in the appended claims.

The drawing illustrating this invention is a diagram of the circuits and apparatus.

In the drawing, A and B designate way-stations and C, D and E telephone circuits terminating at said way-stations, the circuit D connecting said stations together while the circuits C and E extend in opposite directions from the stations A and B to other stations not shown. Connected in bridge 50 of the circuit D at the stations A and B respectively are two receiving telephones 5 and 6 of the loud speaking type.

7 and 8 designate receiving telephones connected in the circuits C and E respectively at terminal stations A and B.

Located at the stations A and B are switch keys 10, 11, 12 and 13 of the double-throw type each being a two-positioned key, one position, that shown as the lower, preferably being a locking position and the other, that shown as the upper, being a non-locking position. Located at each of the stations is a telephone set 15 comprising a transmitter 16, a local battery 17, an induction coil 18 the primary of which is in series with the local battery and the transmitter and secondary of which is adapted to be bridged across the line wires of either circuit C or D as will be hereinafter more fully explained. A key 19 is provided for closing the transmitter circuit and has also a contact in the secondary circuit. Also located at each of the stations is a vibrating signaling device 22 having a local circuit controlled by either of the switch keys located at that station and being provided with an inductive winding 23 which, when either of the keys located at the corresponding station is operated into its locking position, is connected with the line wires corresponding to that particular key. A spring jack 25 located at each of the stations is connected with line wires 26 and 27 leading through a local telephone set 28 having a magneto 29 adapted when operated to operate a signal 30 at the way-station. A plug 31 adapted for insertion into the jack 25 is connected with a telephone receiver 32 and with the telephone transmission apparatus hereinbefore described through contacts on one of the switch keys located at that station. While only one spring jack 25 is shown at each station it will be readily understood that any number within reasonable limits may be provided to enable various parties to talk with the operator at the various stations.

Resistance devices 38 and 39 located at each of the stations are so connected with the contacts of the two keys at their corresponding station that the operation of one of the keys after connecting the transmission apparatus with its corresponding circuit connects one of the resistances in bridge of the other circuit and in shunt of the receiver connected with that circuit at the station at which the key is operated. This feature may be more clearly understood by tracing the circuits established in this operation, and which are as follows: Assume that the oper-

2

ator at station A desires to communicate with the operator at the distant end of circuit C either on a call made by the operator at A or one made to him. The call having been made, the operator at A will operate his key 10 into its non-locking position to actuate the corresponding springs and will also depress his key 19 to close his transmission circuit. Assuming that he has completed this operation, it will be noted that he has closed his local transmitter circuit and the secondary circuit and thus completed the talking circuit over the lines of C which may be traced as follows: from line wire 49, through contact 41 of the key 10, conductor 42, secondary of the induction coil 18, contact 43 of the key 19, conductor 44, contact 45 of the key 10, conductor 46 to the other line conductor 47 of the circuit C. This completes the circuit for the outgoing voice currents from the station A over the line C. Simultaneously with the completion of this circuit, however, other contacts on the key 10 are closed which connect the resistance 39 in bridge of the wires of the circuit D, this circuit being traced as follows: from conductor 50 of the circuit D, conductor 51, resistance 39, contact 52 of the key 10, conductor 53 and conductor 54 to the other line conductor 55 of the circuit D. The resistances 38 and 39 are low as compared with the resistances of the receiving telephones 5, 6, 7 and 8 and consequently afford a considerable shunt to these instruments, thus enabling the operator when talking over one of the circuits to effectively reduce the volume of sound which would result from the operation of the adjacent receiver in the other circuit in case the operator at the opposite end to that particular line should signal or talk. This reduction, however, is not so great but that the operator talking over one line circuit will be aware of a signal or communication sent over the other line circuit terminating in his office. Similarly, the operation of the key 11 into its non-locking position will connect the operator at A for communication with the operator at B, shunt the receiver 7 with the resistance 38, and operatively connect the telephone set 15 with the circuit D.

Referring now to the method by means of which one operator signals another, this may be best understood by following the circuits involved in the process. Assuming that the operator at station A desires to signal the operator at station B he does so by operating key 11 into its locking position to open and close the corresponding contact springs. The actuation of this key into this position closes a local energizing circuit for the signal 22 which may be traced from one side of the battery 60, conductor 61, vibrating contact 62 of the signal, the energizing

winding of the signal 22, conductor 63, conductor 64, contact 65 of the key 11, conductor 67 and conductor 68 to the other side of the battery 60. As this contact vibrates, it induces a current in the winding 23 which will be heard as a tone at the distant end of circuit D, the path for this induced current being as follows: from conductor 55 over conductors 54 and 70, contact 71 of the switch 11, conductor 72 through the inductive winding 23 of the relay, conductor 73, contact 74 of the key 10, conductor 75, conductor 76, contact 78 of the key 11, conductor 79, conductor 50 of the circuit D, and over this line wire through the receiver 6 to the conductor 55. This produces a tone which will be audible in the receiver 6 connected at the other end of the circuit D and also will be heard in the receiver 5 connected with the end of the circuit D from which the signal emanates. This tone will notify the operator at station B that communication with him is desired by the operator at station A. If the operator at station B, however, is busy with a communication over the circuit E he will, of course, have operated his key 13 into its non-locking position to bridge the resistance 38 across the line wires of the circuit D in a manner similar to that traced at the station A. With this resistance in bridge of the wires of the circuit D the volume of the sound in the receivers 5 and 6 resulting from the operation of the signal 22 will be greatly reduced, thus indicating to the calling operator that the operator at the distant end of the line is busy. The key 11 being adapted to lock in its operated position, the operator at station A by leaving this key in its locked position will be able to determine immediately the completion of the communication at the other station by reason of the fact that as soon as this conversation is completed, the key 13 will be released, thus opening a circuit of the resistance 38 which will be immediately noticeable by the increased tone upon the line. Obviously a scheme of this sort provides a convenient and efficient means for obtaining the best results in the system to which it is applied, enabling an operator to carry on a communication with any other operator without disturbance from an adjacent line and still be sufficiently in touch with said adjacent line that any communication of importance can be given immediate attention. This feature is particularly important in railway work where the system may be used for receiving and giving orders for the movement of trains.

What I claim is:

1. In a telephone transmission system, two independent telephone circuits terminating at one station, receiving telephones connected one in each of said circuits, transmission apparatus at said station, means for operatively connecting said transmission appara- 125

tus with either of said telephone circuits and means for reducing the volume of sound in the receiving telephone of either of said circuits when the transmission apparatus is operatively connected with the other of said circuits.

2. In a telephone transmission system two independent telephone circuits terminating at one station, a receiving telephone connected in each of said circuits, transmission apparatus at said station, volume reducing means for each of said receiving telephones, and means for operatively connecting said telephone transmission apparatus with one

15 of said circuits and simultaneously rendering effective the volume reducing means of the receiving telephone in the other of said circuits.

3. In a telephone transmission system, two independent telephone circuits terminating at one station, receiving telephones connected one in each of said circuits and located at said station, transmission apparatus, switching means for operatively connecting said 25 transmission apparatus with either of said telephone circuits and a normally disabled resistance device for each line circuit connected in shunt of the receiving telephone of its line when the transmission apparatus is operatively connected with the other of said lines.

4. In a telephone transmission system, two independent telephone circuits terminating at one station, receiving telephones connected one in each of said circuits, normally disabled resistances for said circuits, transmission apparatus, switching means for operatively connecting said transmission apparatus with one of said telephone circuits and 35 simultaneously connecting one of said resistances in shunt of the receiving telephone in the other of said circuits.

5. In a telephone transmission system the combination of two telephones in audible, interfering proximity, a separate main circuit for each, transmitting apparatus, a switching device and means whereby said switching device when operated places the

transmission apparatus in circuit with one receiver and renders the articulation of the 50 other receiver practically inaudible.

6. In a telephone transmission system, two independent telephone circuits terminating at one end in a common station and at their opposite ends in separate stations, receiving 55 telephones one in each circuit at said common station, and in each circuit at the separate stations, means for reducing the volume of sound in any of said receiving telephones of any of said lines and means at the opposite end of the same line for determining the condition of said receiving telephone.

7. In a telephone transmission system two independent telephone circuits terminating at one end in a common station and at their 60 opposite ends in separate stations, receiving telephones one in each circuit at each of said stations, transmission apparatus at each of said stations, means for operatively connecting said transmission apparatus with the one line terminating at the common station and shunting the receiving telephone of the other line, and means for impressing a tone upon the line at any station the volume of said tone being determined by the condition 65 of the receiver at the opposite end of the line upon which it is impressed.

8. In a telephone transmission system two independent telephone circuits terminating at one end in a common station and at their 80 opposite ends in separate stations, receiving telephones one in each circuit at each of said stations, telephone transmission apparatus at each of said stations, tone inducing means at each of said stations and a two position 85 switch and connections whereby said switch when in one position connects said transmission apparatus with a line and in its other position operatively connects said tone inducing means with the same line.

In witness whereof, I hereunto subscribe my name this 17th day of July A. D., 1912.

HENRY C. EGERTON.
